UNITED STATES PATENT OFFICE

AMOS E. NORTHUP, OF PLEASANT RIDGE, MICHIGAN, ASSIGNOR TO THE MURRAY CORPORATION OF AMERICA, OF DETROIT, MICHIGAN, A CORPORATION OF DELAWARE

DESIGN FOR AN AUTOMOBILE BODY

Application filed February 17, 1932. Serial No. 42,895. Term of patent 3½ years.

To all whom it may concern:

Be it known that I, AMOS E. NORTHUP, a citizen of the United States, residing at Pleasant Ridge, in the county of Oakland, State of Michigan, have invented a new, original, and ornamental Design for Automobile Bodies, of which the following is a specification, reference being had to the accompanying drawings, forming a part thereof, wherein—

Figure 1 is a perspective view of the forward end and side of the automobile body.

Figure 2 is a perspective view of the rear end and opposite side of the automobile body.

The dominant feature of my new design comprises the appearance of the forward corners and parts surrounding the wind-

shield, as shown in the full lines. The parts shown in the dotted lines are illustrative of a conventional standard type of automobile body, except the rear end shown in dot-and-dash lines (Fig. 2) which is the subject of my co-pending application Serial No. D-43956 filed June 2, 1932. The said dominant feature may be employed and embodied without substantial change, in the following conventional types of closed automobile bodies: coupés, four-door sedans, coaches or two-door sedans and victorias.

I claim:

The ornamental design for an automobile body, substantially as shown and described.

AMOS E. NORTHUP.
